UNITED STATES PATENT OFFICE.

JAMES BRACE, OF FROSA, TEXAS.

CHURN-POWER.

SPECIFICATION forming part of Letters Patent No. 231,000, dated August 10, 1880.

Application filed June 24, 1880. (Model.)

To all whom it may concern:

Be it known that I, JAMES BRACE, of Frosa, in the county of Limestone and State of Texas, have invented a new and valuable Improvement 5 in Churn-Powers; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a front view of my improved motor, partly in section, and Fig. 2 is a detail view of the 15 cross-head.

This invention has relation to improvements in churn-motors wherein rotary motion is converted into reciprocating motion; and it consists in certain novel combinations of parts, as 20 hereinafter fully shown and described.

In the annexed drawings, the letter A designates the base of the motor, having erected thereon the three parallel uprights B B' B''. Between the uprights B' B'' is arranged a 25 master gear-wheel, C, actuated by a crank or other mechanism, and engaging a small gear or pinion, D, keyed or arranged upon a short shaft, E, having its bearings in the upper ends of the said uprights, as shown in Fig. 1. This 30 shaft is provided at its end, contiguous to upright B', with an enlarged head, a, through which is formed a perforation, i, at right angles to the axis of rotation of the said shaft, and a screw-threaded perforation, i', ending at 35 perforation i and at right angles thereto. In the upper end of the upright B is a second shaft, F, having its axis of rotation in line with that of shaft E, and, like it, provided with a head, b, having the through-perforation e 40 and the threaded perforation e'.

G indicates a double crank, composed essentially of the wrist or pin b', having the central collar, b'', and the cheek-arms e, fitted removably on the ends of said wrist and extending 45 up through the perforations i and e of the heads a and b.

The shanks of the arms e are provided with notches or depressions d at regular intervals, and move readily endwise, being adjusted to 50 regulate the throw of the crank by means of the set-screws s extending through the perforations i' e' of the heads and engaging the depressions d aforesaid.

H H' designate pitmen, having at their 55 upper and lower ends, respectively, the eye-

rings f' f'', that are passed upon the wrist of the crank and over the ends of a cross-head, I, moving vertically in guides g on the inner faces of the uprights B B'. The rings f'' of these pitmen are maintained against the collar b'' by means of the sleeves g', applied on the wrist inside of the cheeks of the crank.

The cross-head I is constructed with a horizontally-vibrating hinged gate, h, which opens for the admission of the dash-rod J of the 65 churn, the recesses of half-round form being formed in the contiguous faces of the body of the cross-head and of the gate for its reception. The gate is caused to clamp the rod against the body of the cross-head by a set-screw, k, extending through threaded perforations therein. The cross-head is illustrated in Fig. 2. By regulating the throw of the crank the movements of the plunger may be regulated according to the quantity of cream in the barrel K and according to the height of the barrel itself.

If desired, instead of the master-gear and pinion above described, in instances where a long stroke of the dash-rod is required, as in 80 large barrels, I may use rag or chain wheels connected by an endless chain-belt.

What I claim as new, and desire to secure by Letters Patent, is—

1. In a churn-motor, the parallel uprights B B', the shafts E F, journaled in their upper ends, and provided at their adjacent ends with the heads a b, having through-holes i e and screw-holes i' e', the crank G, having cheek-arms e extending up through perforations i e 90 and provided with depressions d, the set-screws s, the pitmen H H', cross-head I, and guides g, the whole combined and arranged to operate substantially as specified.

2. In a churn-motor, the combination, with 95 the frame B B', guides g, and cross-head I, of the shafts E F, in line with each other, and having the heads a b, the double crank G, adjustably secured to said heads, the pitmen H H', connecting said cross-head to the crank, 100 and the dash-rod J, secured to said head, substantially as specified.

In testimony that I claim the above I have hereunto subscribed my name in the presence of two witnesses.

JAMES BRACE.
